ABSTRACT OF THE DISCLOSURE

Car wash apparatus in which an overhead brush which washes the roof and rear end portion of the car is supported to permit the brush to move in the direction of the car as the brush moves into contact with the rear portion of the car moving past the apparatus.

BACKGROUND OF THE INVENTION

This invention relates to car washing equipment and particularly to an apparatus for supporting an overhead brush which is arranged to wash the roof, trunk, and rear end portion of the car.

In the present day car washes, there is usually provided a cleaning station having an overhead brush which is adapted to wash the hood, roof and trunk of the car. These brushes typically are mounted on a pivotal support whereby the brush is supported at the end of a pivoted frame which extends from the pivot axis in the same direction as the direction of movement of the car through the apparatus and past the cleaning station. This arrangement is not entirely satisfactory, particularly in the case of station wagons, since, as the car moves past the brush and the brush pivots downwardly past the rear end portion of the car, the brush moves away from the car and cannot make a very effective contact with the car. Since this overhead brush arrangement does not wash the rear end portion of the car, present day car washes employ a separate rear end washing means usually in the form of a "wrap around" brush.

SUMMARY OF THE INVENTION

It is the general object of this invention to provide a car washing apparatus wherein the overhead brush for the roof and rear of the car is supported so that it will provide an improved washing action. Briefly stated, this object is achieved by the provision of a movable support for the brush which permits the brush to move in the direction of car movement as the rear end portion of the car moves past the cleaning station. This arrangement permits a longer period of contact between the brush and the rear end portion of the car and an improved contact pressure between the brush and the car. This is particularly advantageous for the cleaning of the rear end portion of a station wagon.

BRIEF DESCRIPTION OF THE DRAWINGS

FIG. 1 is a perspective view illustrating the car wash apparatus in accordance with the invention; and

FIGS. 2A through 2F are schematic illustrations showing the sequential stages of the car movement through the car washing apparatus and illustrating the car washing action in accordance with the invention.

DESCRIPTION OF THE PREFERRED EMBODIMENT

The apparatus in accordance with the invention is utilized in a conventional car wash at a station whereat the roof, trunk and the rear end portion of the car are to be brush cleaned. The other parts of the car are cleaned, washed and dried at other stations of the car wash. As is conventional in the art, the car is connected to a con-

2

veyor which pulls the car in a straight path through the car wash past the various cleaning, washing and drying stations. Such means are conventional and form no part of the present invention which relates to the construction and arrangement of an apparatus for supporting a rotating brush which is adapted to clean the roof, trunk and rear end portion of the car as it passes the cleaning station.

Referring to FIG. 1, the apparatus in accordance with the invention comprises a pivoted frame, indicated generally at 10, mounted above the path of travel of the car through the car wash and past the cleaning station. The frame 10 includes a pivot bar 12 which extends transversely across the path of travel of the car (which is shown by the arrow in FIG. 1) and is rotatably mounted at its ends on suitable bearings 14 and 16 which are mounted on the main frame 18 of the cleaning station which is supported on the floor of the car wash. A pair of elongated members 20 and 22 are mounted at a central portion thereof on the pivot bar 12 for movement therewith. The members 20 and 22 extend in parallel relation and are spaced apart a considerable distance which desirably is somewhat greater than the width of a car. The members 20 and 22 extend at right angles to the pivot bar 12 and thus extend in planes parallel to the path of travel of a car through the car wash. The members 20 and 22 are connected together at their ends which adds to their structural strength. At the ends of members 20 and 22 which extend from the pivot bar 12 in the direction opposite to the direction of car movement, the members 20 and 22 carry a rod 24 which extends transversely across the car wash station and is supported by a pair of two-hole flange bearings 26 and 28 on the members 20 and 22, respectively. At their opposite ends, members 20 and 22, carry a transversely extending counterweight 30, the purpose of which will appear more fully hereafter.

Means are provided for rotatably supporting a car washing or cleaning brush on the end of the frame 10 which carries the pivot rod 24. Such means comprises a pair of frame members 32 and 34 which are mounted at upper portions onto the ends of rod 24 at the bearings 26 and 28, whereby members 32 and 34 pivot about the axis of rod 24. The members 32 and 34 extend in parallel relation as is shown in FIG. 1 and are connected at their upper ends by a cross member or spacer 35 and at a location below bar 24 by a second cross member or spacer 36 whereby the members 32 and 34 are connected together in a unitary frame structure 38. Member 36 is a U-shaped channel which contains a water spray pipe 37 which directs sprays of water downwardly onto the brush therebeneath as is conventional in the art. Water is supplied to pipe 37 by way of a conduit 39. At their lower ends members 32 and 34 carry a brush shaft 40 which is rotatably mounted in a pair of bearings 42 and 44 which are mounted on the lower ends of the members 32 and 34, respectively. The brush shaft 40 is adapted to rotatably support a suitable brush 46 shown in dashed lines in FIG. 1. The brush 46 may take any of the suitable forms well known in the art.

The counterweight 30 is designed to approximately balance the weight of the brush 46 and the supporting frame 38. Accordingly the frame 10 is maintained in a balanced condition on pivot bar 12.

By reason of the construction described above, it will be apparent that the brush carrying frame 38 is pivotally mounted onto the frame 10 at the end thereof carrying the rod 24. There is provided a stop member 50 mounted on the member 22 at a location adjacent the upper end of member 34, the stop member 50 being adapted to contact the upper end of member 34 to limit the movement thereof. The parts are constructed and arranged so that

the stop member 50 will limit the movement of the frame 38 in the clockwise direction about the axis of bar 24 as viewed from the right in FIG. 1. This limit of movement occurs when the frame 38 extends at right angles to the frame 10. It will be noted that the frame 38 is free to pivot in a counterclockwise direction from the stop position about the axis of rod 24 as viewed from the right in FIG. 1. The purpose of this arrangement will become apparent hereafter.

Means are provided for biasing the frame 38 towards pivotal movement in the counterclockwise direction about the axis of rod 24 away from the stop member 50. Such means comprises a hydraulic cylinder means 52 which is pivoted at one end on a bracket 53 on member 22 and has the extended end of its actuator arm 54 (which is connected to a piston within the cylinder) connected to a member 56 mounted on the spacer 35. Hydraulic fluid is supplied to one end of the cylinder 52 (i.e. on one side of the piston therein) through a hose 58 which is connected to a supply container 60 for hydraulic fluid. Air pressure is supplied to the upper end of the container 60 through a hose 62 which extends from an air pressure source (not shown). The source is such that a relatively low and constant pressure is maintained. By this arrangement, the hydraulic cylinder 52 will apply a constant force to the upper end of the frame 38 to tend to urge the same to pivot in a clockwise direction about the axis of rod 24. It will be noted that this force may be overcome by the application of a more powerful force to the member 38 in the opposite direction and the cylinder means 52 will accommodate such a force.

The frame 38 also carries means for causing rotation of the brush shaft 40. Such means comprises a motor 66 mounted at the upper end of member 32. The motor 66 is drivingly connected to an endless drive chain 68 which is connected to a sprocket on the end of the brush shaft 40 supported on member 32. In this manner the operation of the motor 66 causes the movement of the drive chain 68 to cause rotation of the brush shaft 40. The brush is rotated in the direction of the arrows in the drawings.

Means are provided for applying a force to the frame 10 to urge the same in a counterclockwise direction about the axis of pivot bar 12 as viewed from the right of FIG. 1. Such means comprises a hydraulic cylinder 70 which is pivoted at one end to an upright support member 71 and which has the extended end of its actuator arm 72 (which is connected to a piston within the cylinder) connected to a pivot arm 74 secured to pivot bar 12 and projecting upwardly therefrom as viewed in FIG. 1. Hydraulic fluid is supplied to one end of hydraulic cylinder 70 (i.e. on one side of the piston therein) by a hose connection 76 from a supply of hydraulic fluid in a container 78 supported on upright 71. Air pressure is applied to the upper portion of container 78 to cause the hydraulic fluid to move into the cylinder 70 to cause an extension of the actuator rod 72 when it is desired to effect a pivoting action of the frame 10. The air pressure applied to container 78 is controlled by a suitable cam actuated control valve means 80 which is adapted to vary the pressure applied to the container 78. The control means 80 is of any type well known in the art and is such that during a cycle of operation the air pressure applied to container 78 increases. The purpose of this will become more apparent during the description of the operation of the apparatus in accordance with the invention.

There will, of course, be provided various control means as is conventional in the art starting and stopping the cycle of operation and for insuring safe operation.

There is also provided a stop member 86 mounted on an upright 88 and adapted to contact arm 74 to limit the clockwise movement (as viewed from the right in FIG. 1) of pivot bar 12 and frame 10. The stop 86 is positioned to prevent the piston in cylinder 70 from contacting the upper end of this cylinder during a clockwise

movement of the frame 10 as will be described hereafter. The operation of the apparatus in accordance with the invention is illustrated in FIGS. 2A through 2F. In FIG. 2A the apparatus is shown in the condition when the brush 46 has just come into contact with the front end of the roof of the car, the parts assuming the position generally shown in this figure. It will be noted that the frame 38 extends at an acute angle with the frame 10, this being achieved by the biasing action of the cylinder means 52.

The next stage in the operation is shown in FIG. 2B, wherein the brush is shown on top of the roof of the car. It will be noted that the acute angle has been decreased considerably, this being caused by the friction of the rotating brush 46 in contact with the roof of the car and by reason of an increase in the pressure applied by the cylinder 70 by way of the control valve means 80. The frictional contact of the brush with the car causes the brush to move away from the axis of pivot bar 12.

In FIG. 2C the brush 46 is shown as it is leaving the rear end of the roof of the car and it will be noted that the frame 38 extends at right angles to the frame 10. This being achieved by the application of a substantial pressure by the cylinder 70 which forces the brush 46 downwardly to apply considerable pressure onto the roof of the car thereby increasing the friction between the rotating brush and the car which causes the brush to move along the car until this movement is halted by the stop member 50 coming into contact with the member 34.

In FIG. 2D, the car is shown in a position where the brush 46 is rotating against the rear window of the car to effect a cleaning thereof. It will be noted that the frames 10 and 38 have been pivoted downwardly slightly from the position shown in FIG. 2C to follow the contour of the car. This is achieved by the continued pressure being applied by the cylinder 70, which pressure is increased over that applied in the condition shown in FIG. 2C.

In FIG. 2E, the car has moved to the position whereat the brush 46 contacts the end of the trunk and the brush 46 has moved slightly downwardly along the rear end of the car. It will be noted that the frames 10 and 38 are moved downwardly slightly from the position shown in FIG. 2D. Again this is achieved by the action of the cylinder 70, the frictional contact of the brush 46 with the car serving to overcome the action of the bias applied by the hydraulic cylinder 52.

In FIG. 2F the car has moved to the position whereat the brush 46 is acting at a central portion on the rear end of the car, the pressure applied by cylinder 70 being at the maximum. It will be noted that the frames 10 and 38 have tilted downwardly and the brush 46 has moved along with the car to maintain its contact with the rear end of the car as the car moves from the position shown in FIG. 2E to the position shown in FIG. 2F. This is an important feature of the arrangement in accordance with the invention. By reason of the long time in which the brush 46 is maintained in contact with the car and the fact that this contact can be maintained under pressure, a very effective cleaning action may be achieved.

After the car has moved past the cleaning station and the brush 46 has moved to a position such as is shown in FIG. 2F, the cleaning cycle is completed. This is achieved by the control valve means 80 relieving the air pressure applied to container 78. When this occurs, the frames 10 and 38 return to the position shown in FIG. 2A under the action of the counterweight 30. The stop member 86 will limit this return movement to prevent damage to the cylinder 70 as was described above.

It will be apparent that there will be provided suitable control means for insuring that the parts will not remain in the position such as that shown in FIG. 2E or 2F but will be returned to the position shown in FIG. 2A after a car has moved past the cleaning station. If this were not the case, the next car coming into the car washing station would come into contact with the frame 38 and

possibly be damaged. Such control means are well known in the art and generally involve a timer, as shown at 82 in FIG. 1, which is energized at the start of the cycle and provides a control signal after a predetermined time corresponding to the time when a car would move past a station. In this case the timer signal will be applied to the control means 80 for the hydraulic cylinder 70 to actuate the same to cut off the application of the air pressure and allow the frame 10 and the frame 38 carried thereby to return to the upward position such as that shown in FIG. 2A by reason of the counterweight action. In addition there may be provided a safety switch 90 which is contacted by the car to actuate a control which causes the frame 38 to return to the position shown in FIG. 2A.

However, another feature of the invention is that the construction is fail safe in that even if a car should pass into the station with the frames 10 and 38 in a downward position (which could occur if the timer 82 and switch 90 failed), as soon as the car would contact the brush 46 to move it forwardly toward the pivotal axis 12 (this movement is permitted by reason of the mounting of frame 38 on frame 10 as described above), this would decrease the weight tending to cause the frames 10 and 38 to pivot in a counterclockwise direction and the counterweight 30 would cause an unbalance and operate to actually lift the frames 10 and 38 upwardly. In this way, the mechanism is fail safe and will operate safely mechanically even if other control means fail.

It will be apparent that various changes may be made in the construction and arrangement of parts without departing from the scope of the invention. For example, the location and arrangement of the counterweight means may take various forms. Accordingly, it is not desired to be limited except as required by the following claims.

I claim:

1. For use in a car wash in which a car is moved along a path of travel through the car wash and past a cleaning station for the top and rear end portions of the car, an apparatus for supporting a rotating brush at said station comprising first support means for rotatably supporting the brush to extend above and transversely of the path of travel of the car, second support means for movably supporting said first support means, said second support means including a pivot means extending transversely of the path of travel of the car and a supporting frame mounted on said pivot means and extending therefrom in the direction opposite to the direction in which the car moves in its path of travel past said cleaning station, said first support means being mounted on an extended portion of said support frame so that the brush is supported for movement downwardly and forwardly in the direction of travel of the car past said cleaning station.

2. An apparatus according to claim 1 wherein the

mounting of said first support means on said supporting frame comprises a pivotal mounting means permitting said first support means to pivot in the direction of car travel.

3. An apparatus according to claim 2 including stop means for limiting the pivotal movement of the first support means relative to said second support means in the direction away from the pivot of the second support means, said stop means being located so that at said limited location the first support means extends approximately perpendicularly to said supporting frame.

4. An apparatus according to claim 1 wherein said supporting frame has a portion extending from said pivot means in the direction of movement of the car past said cleaning station, and including a counterweight means mounted on said last-mentioned extending portion to balance the weight of the means mounted on the other extended portion of said supporting frame.

5. An apparatus according to claim 2 including means for biasing said first support means about its pivotal mounting in a direction to cause the brush to move toward the pivotal means for said second support means.

6. An apparatus according to claim 5 in which said biasing means comprises a pressure actuated hydraulic cylinder.

7. An apparatus according to claim 1 including means for urging said supporting frame to pivot about said pivot means in the direction whereby said first support means is moved downwardly and in the direction of movement of the car past said cleaning station.

8. An apparatus according to claim 7 in which said urging means comprises a pressure actuated hydraulic cylinder and means for varying the force applied by said hydraulic cylinder.

9. An apparatus according to claim 5 including means for urging said supporting frame to pivot about said pivot means in the direction whereby said first support means is moved downwardly and in the direction of movement of the car past said cleaning station.

10. An apparatus according to claim 9 in which said urging means comprises a pressure actuated hydraulic cylinder and means for varying the force applied by said hydraulic cylinder.
